UNITED STATES PATENT OFFICE

EDWIN W. BEREIT, OF MENTOR, OHIO, ASSIGNOR TO THE CLEVELAND CRANE & ENGINEERING COMPANY, OF WICKLIFFE, OHIO, A CORPORATION OF OHIO

LOAD BAR

Application filed January 8, 1930. Serial No. 419,422.

This invention relates to suspended carriers of the monorail type, and more particularly to a load bar for such carriers.

An object of this invention is to provide 5 an improved form of load bar for traveling carriers.

Another object of this invention is to provide a form of carrier load bar which can be cheaply manufactured from commercial 10 rolled stock.

The invention may be further briefly summarized as consisting in certain novel combinations and arrangements of parts herein-after described and particularly set out in 15 the appended claims.

In the accompanying sheet of drawings, Figure 1 is a side elevational view showing the outline of a suspended carrier embodying the load bar of my invention.

20 Figure 2 is a top plan view of the bar.

Figure 3 is an end elevation of a suspended carrier with parts thereof broken away showing the load bar in assembled relation, and

25 Figure 4 is a side elevational view of a bar of stock used in constructing my load bar.

In the drawings illustrating my invention, I have shown my load bar embodied in a suspended carrier of the monorail type, but it will be understood, of course, that the load 30 bar of my invention may be embodied in carriers of various types. Load bars, as heretofore used in carriers of this kind, have generally been constructed in the form of castings, and because of the many defects which

35 castings are inherently subject to, load bars of that form of construction are unreliable and are frequently broken during service of the carriers.

I have found that more reliable and more 40 durable carrier load bars of this type, can be more cheaply manufactured from bars of commercial rolled stock, and in the drawings I have shown a load bar of this type of construction embodied in a suspended carrier.

45 This carrier comprises heads 10 and 11 suspended from a monorail 12, and a substantially horizontal load bar 13 pivotally connected adjacent its ends to the heads. The carriers heads may be constructed according 50 to any suitable design, but as illustrated in

the drawings, each head is made in the form of a U-shaped yoke 14, having wheel mounting bearing members 15 secured to the ends thereof. By means of these bearing members each yoke is suspended from a pair of wheels 55 16, adapted to travel along the laterally extending flanges 17 of the rail 12. The yokes are each provided with a strut 18, which extends between and is secured to the legs of the yoke in spaced relation to the intermediate straight portion 19 of the yoke.

Another object of this invention is to provide a form of carrier load bar which can be cheaply manufactured from commercial 60 rolled stock.

The load bar, according to my invention, is preferably made up of two sections 20 and 21 of commercial rolled stock, such as steel channel-shaped bars, which are readily available 65 in all desired sizes. These sections are arranged back to back as shown in Figure 2, in spaced, substantially parallel relation. To reduce the depth of the end portions of the load bar, I cut out web portions adjacent the 70

ends of each of the sections of rolled stock, as clearly shown in Figure 4. The openings thus formed in the webs of the sections are then closed by bending the flanges toward 75 each other to bring the cut edges 22 of the web into meeting relation along the lines 23, as indicated in Figures 1 and 3. After the web portions have thus been cut out and closed, the meeting edges of the web may be welded together if desired along the lines 23. 80

For supporting the load bar I provide bearing members 24 mounted upon the reduced end portions of the sections. These bearing members are preferably secured in place by being welded to the top and bottom flanges 85

of both sections. These members may be constructed of any suitable shape but, as here illustrated, are shown circular in form, and are arranged with their central openings 90

in aligned vertical relation with each other, and with the space 26 between the backs of the sections. While any suitable means may be employed for rigidly connecting the sections together, the bearing members when 95

welded to the flanges of the sections also accomplish this purpose.

Bumpers 27 may be secured at the ends of the load bar if desired. These bumpers may be constructed in any suitable form, and when secured to the ends of the sections, as by weld- 100

ing, they assist in holding the sections together.

At its mid portion the load bar may be provided with a U-shaped member 28, which is securely welded or otherwise fastened to the sections. This member also assists in holding the sections together, but its principal function is to form a suitable mounting for attaching the load which the carrier is to support.

10 When the load bar is assembled in place, as shown in Figure 3 of the drawings, the reduced end portions of the bar are received between the struts and the intermediate straight portions of the yokes. At each end of the bar the top bearing member 24 engages the lower flat surface of the strut 18, while the lower bearing member 24 engages the upper flat surface of the intermediate straight portion 19. Suitable openings 29, provided through the strut and the intermediate straight portion, align with each other and with the openings of the bearing members 24, to receive the king pin 30. The ends of the load bar are thus pivotally and detachably connected to the respective carrier heads.

It will now be readily understood that I have provided a strong and reliable form of load bar, which can be cheaply constructed from bars of commercial rolled stock. Load bars, constructed in this manner according to my invention, are very rugged, and are not likely to fail in service.

It should be noted that in forming the reduced ends of the load bar, only web portions of the sections are cut out thus leaving ample metal to provide sufficient strength to carry the desired load.

While I have shown and described the device of my invention in a detailed manner, it should be understood, however, that I do not intend to limit myself to the precise details shown and described, but regard my invention as including such changes and modifications as do not involve a departure from the spirit of the invention and the scope of the appended claims.

Having thus described my invention, what I claim is:

50 1. In a load bar for a carrier the combination of a member having portions between the opposite edges thereof cut out and bent shut to form end portions of reduced depth, and means welded to said reduced end portions to provide bearing surfaces for said bar.

2. A load bar for a carrier comprising sections of rolled stock arranged in substantially parallel relation, said sections having web portions thereof cut out and closed forming reduced end portions, and means welded to said reduced end portions to provide bearing surfaces on said bar.

3. A load bar for a carrier comprising sections of rolled stock arranged in substantial-

ly parallel relation, said sections having web portions thereof cut out and closed to provide reduced end portions, the meeting edges of said closed web portions being welded together, and bearing members for supporting said bar welded to said reduced end portions.

4. A load bar for a carrier, comprising a plurality of adjacent sections of rolled stock, and means welded to said sections to provide bearing surfaces for said bar.

5. A load bar for a carrier comprising a plurality of channel-shaped sections of stock arranged back to back in spaced, parallel relation, and bearing members welded to the flanges of said channel-shaped sections, said bearing members having openings aligned with the space between said sections and adapted to receive a pin.

6. A load bar for a carrier comprising a plurality of substantially parallel sections of stock, and means welded to said sections to provide bearing surfaces for supporting said bar adjacent the ends thereof.

7. A load bar for a carrier comprising member secured together in substantially parallel relation, said members having portions between the top and bottom edges thereof cut out and bent shut and welded together to provide the bar with end portions of reduced depth, means welded to said reduced end portions to provide said bar with bearing surfaces, and a U-shaped load supporting clip welded to said members intermediate said bearing surfaces.

8. A load bar for a carrier comprising members secured together in substantially parallel relation, said members having portions between the top and bottom edges thereof cut out and bent shut and welded together to provide the bar with a reduced end portion, and a bumper secured to said reduced end portion.

9. A load bar for a carrier comprising members secured together in substantially parallel relation, said members having portions between the top and bottom edges thereof cut out and bent shut and welded together to provide the bar with a reduced end portion, a bumper secured to said reduced end portion, and supporting bearing surfaces on said reduced end portion.

In testimony whereof, I hereby affix my signature.

EDWIN W. BEREIT.
